INVENTOR
Lewis J. Greenawalt.
BY
Berney & Barr
ATTORNEY

UNITED STATES PATENT OFFICE.

LEWIS J. GREENAWALT, OF MANSFIELD, OHIO, ASSIGNOR TO WESTINGHOUSE ELECTRIC PRODUCTS COMPANY, A CORPORATION OF MICHIGAN.

ELECTRIC CIGAR LIGHTER.

Application filed May 9, 1923. Serial No. 287,647.

To all whom it may concern:

Be it known that I, LEWIS J. GREENAWALT, a citizen of the United States, and a resident of Mansfield, in the county of Rich-
5 land and State of Ohio, have invented a new and useful Improvement in Electric Cigar Lighters, of which the following is a speci-
fication.

My invention relates to electric heating
10 devices and particularly to electric cigar
lighters.

The object of my invention is to provide
an electric cigar lighter of relatively simple
and compact structure.

15 In practicing my invention, I provide a screw plug of refractory material upon which are mounted the usual contact terminals. A relatively thin sheet of electric insulating material of substantially square form has mounted thereon a resistor member comprising a relatively thin sheet of resistance material, also of substantially square form, having a plurality of slots therein extending alternately from opposite sides
20 thereof. The resistor member is secured on the sheet of insulating material by having its corner portions return-bent over the edges of the sheet, the two sheets being located diagonally of each other. Integral
25 terminal extensions are provided for the resistor member and are connected to the contact terminals.

An annular member of electric-insulating material is located against the outside face
30 of the resistor sheet and an annular cap member of metal holds the assembled resistor and supporting plate in their proper operative positions against the open end of the refractory screw plug.

40 In the single sheet of drawings,

Figure 1 is a view, partly in side elevation and partly in vertical section, of a device embodying my invention.

Fig. 2 is a top plan view thereof.

45 Fig. 3 is a top plan view of a resistor member.

Fig. 4 is a top plan view of the resistor member mounted on its supporting plate and,

50 Fig. 5 is a view in end elevation of the members shown in Fig. 4.

A heating device 11 comprises a member 12 of refractory material and having sub-stantially the form of a screw plug and is

of such dimensions as to fit into an ordinary
screw socket.

The threaded portion of the member 12 is provided with an annular metal member 13 that is formed with screw threads to permit of its being mounted in its proper operative position on the screw-threaded portion of the member 12 substantially as illustrated in Fig. 1 of the drawing. The member 13 constitutes one of the terminals of the device in a manner well known in the art. The other terminal of the device is constituted by a machine screw 14 that is located in, and extends through, an opening 15 in the otherwise closed end of the screw plug member 12, a nut 16 being provided on its inner screw-threaded end in order to hold the bolt 14 in its proper operative position substantially as illustrated in Fig. 1 of the drawing.

55 A resistor member 17 comprises a relatively thin sheet of resistance material, which sheet is provided with a plurality of longitudinally-extending spaced slots 18 that extend alternately from opposite edges of the sheet whereby a relatively long and narrow path is obtained to be traversed by the current when the resistor member is connected to a suitable source of electric energy.

60 Integral, relatively narrow, terminal portions 19 and 21 are provided on the member 17 to permit of the connection of the resistor member proper to the hereinbefore described terminal members of the device. In order to permit of fitting the terminal portions 19 and 21 easily within the screw plug when 65 the resistor member is mounted on its support, as will be hereinafter described, these members are provided with offset portions, as illustrated in Fig. 3 of the drawing.

65 A sheet 22 of relatively thin, electric-insulating material, such as mica, is of substantially square form and is provided with rounded corners 23, the width of the member 22 between the diagonally opposite corners 23 being substantially the same as the outer diameter of an enlarged portion 24 of the screw plug. The sheet 17 has one of its faces located closely adjacent to one of the faces of the plate 22 and the two members are locked diagonally of each other, 70 substantially as illustrated in Fig. 4 of the drawing, in order that the corner portions of the sheet 17 may be return-bent around

the edges of the member 22 whereby the member 17 is maintained in its proper operative position relatively to, and on, the sheet 22.

- 5. The resistor member 17 mounted on the supporting plate 22 is located against the open and enlarged end of the screw plug member 12 and an annular member 25, comprising a relatively thin sheet of electric-insulating material, such as mica, is located against the outer surface of the resistor sheet 17. A metal cap member 26, of annular form, is located with its inner surface operatively engaging the outer surface of the member 25 and is provided with an integral flange portion 27 of such depth that it may be spun over the inner shoulder portion of the enlarged end 24 substantially as illustrated in Fig. 1 of the drawing.
- 10. In assembling the resistor member and its mounting plate on the screw plug member 12, one of the two terminal strips 19 or 21 has its outer end placed in operative engagement with the terminal member 14 and it may be secured thereto either by the use of the nut 16 or it may be permitted to extend through the opening 15 and be soldered into a suitable slot provided in the outer face of the screw 14. The outer end of the other terminal strip is fed through a slot 28 provided in the body of the screw plug 12 and may then be suitably soldered against the member 13. The annular member 25 may then be placed within the cap member 26 and the two members placed in their proper operative positions on the outer open end of the screw plug 12 and the outer edge of the flange 27 spun over.
- 15. The device embodying my invention thus provides a relatively simple and inexpensive construction for an electric cigar lighter comprising relatively few parts and one which may be easily and quickly mounted within an ordinary lamp socket to be energized thereby. If it is found that the resistance of the resistor member 17 is not sufficiently high to permit of its being energized from the ordinary 110 volt circuit, it is, of course, possible to provide a suitable voltage in accordance with the resistance of the member 17 and the amount of energy which it is desired to transform into heat.

Various modifications may be made in the device embodying my invention without departing from the spirit and scope thereof, and I desire, therefore, that only such limitations shall be placed thereon as are imposed by the prior art or are specifically set forth in the appended claims.

16. I claim as my invention:

1. A cigar lighter comprising a tubular refractory member having a closed end, a plate of electric-insulating material opera-

tively engaging said tubular member at its open end, a slotted resistor member supported by said plate of electric-insulating material and secured thereto by integral return bent portions and means for securing said plate and said resistor member against said tubular member.
